CONVERTIBLE COACH AND SLEEPER

Louis W. Martin, St. Louis, and Arthur E. Lehmann, St. Charles, Mo., assignors to American Car and Foundry Company, New York, N. Y., a corporation of New Jersey

Application October 15, 1935, Serial No. 45,072

17 Claims. (Cl. 105—314)

This invention relates to railway passenger cars in general and in particular to that type of car which may be used as either a day coach, parlor car or as a sleeper when desired.

5 The conventional Pullman or sleeping car as constructed is excessively heavy and is under present decreased traffic operated at a loss. The usual sleeper is seldom filled and very often the upper berths are unoccupied which, of course, increases the loss of the railroads due to the needless weight hauled. Also the Pullman car during the daytime is unattractive and compares very unfavorably with the present modern type of cars.

15 It is an object of this invention therefore to provide a railway car which may follow closely the present light weight, attractively decorated day coach, yet which may, when it is so desired, be converted into a sleeper.

20 Another object of the invention is the provision of a railway car in which provision is made for the carrying and application of folding light weight partitions.

Another object of the invention is the provision 25 of a railway car similar in appearance and appointments to the usual day coach, yet which may be converted into either a sleeper or a compartment car.

A further object of the invention is the provision 30 of a railway car of the day coach type in which any desired portion or portions may be used for sleeping purposes.

A further object of the invention is the provision 35 of a new and improved type of seat especially adapted for use in a day coach for conversion into a sleeper.

A still further object of the invention is the provision 40 of a new and improved arrangement of seat parts for a sleeper in order that dressing space is provided between the bed and curtain.

These and other objects and advantages will 45 be apparent to one skilled in the art from a study of the following description taken in conjunction with the accompanying drawings, in which

Figure 1 is an elevational view of a portion of 45 the improved car when made up for use as a sleeper;

Fig. 2 is an elevational view similar to Fig. 1 but showing the car as intended for day use;

50 Fig. 3 is a cross sectional view of the improved car showing on the left the car adapted for day use, while on the right the car is made up for use as a sleeper in which dressing space is provided adjacent the curtain;

55 Fig. 4 is a plan view of the seats shown on the right hand side of Fig. 3 and shows quite clearly

the dressing space available with the improved arrangement;

Fig. 5 is a detail elevational view of the removable and foldable partition;

Fig. 6 is a sectional view taken on line 6—6 of Fig. 5 and shows details of the car receiving pocket and central joint;

Fig. 7 is a detail sectional view taken on line 7—7 of Fig. 5 and shows the bed supporting shelf;

Fig. 8 is an elevational view showing the relation of the parts when the partition is separated and folded for storage;

Fig. 9 is a detail sectional view taken on line 9—9 of Fig. 5 and shows the relation of the partition to the storage bins;

Fig. 10 is a detail view of the removable curtain rod and partition steady device;

Fig. 11 is a side elevational view of a seat and shows the manner of supporting the seat backs when the berth is made up;

Fig. 12 is a perspective view of the back supporting element used in making up the berth;

Fig. 13 is a plan view similar to Fig. 4 but showing a modification in which the pipe rail type of seat is used, and

Fig. 14 is a perspective view similar to Fig. 12 and showing the back supporting element adapted for use with the seats of Fig. 13.

Referring now to the several drawings in detail and first to Figs. 1 to 12 inclusive, the car A is shown as of the monitor deck type built with the conventional framing structure and including the air conditioning duct B. The walkover seats C are formed with the two part backs D and closed type ends E. Storage bins F are provided adjacent the half deck and form part of the interior finish of the car, while short length baggage racks G are positioned on the side wall below the bins and above the windows H.

The seats as stated are of the walkover type provided with cushions 2 and a back formed of a lower part 4 having grooved side members 5 adapted to interlock with projections on back supporting bars 6 which carry a pivoted top back portion 8. The part 4 is readily removed by rotating the portion 8 into the shelf position shown at the right of Fig. 1 and then lifting the lower part slightly to disengage the projections after which it may be pulled out from between the bars. The sides of the seat are joined by a pressed member 10 arched upwardly to provide additional baggage room as well as to form an extended bearing portion for the seat cushion which is carried at its ends on slide bars 12 having cushion engaging projections 14.

Due to the difference of thickness between the backs and cushions it is necessary to provide a supporting member 16 (Fig. 12) having a base portion 18 suitably formed to fit the pressing 10 and engage the slide bars and the projections thereon. The upwardly extending part 20 has a ledge 22 and upstanding flange 24 provided with inclined elements 26. The ledge and elements 26 are provided to support and interlock with portions 5 of the seat back as clearly shown in Fig. 12.

The car is divided into compartments by light weight partitions P formed in two separable parts S and T. The part S is formed by a lower part 28 and upper part 30 hinged thereto and both 15 adapted when unfolded to fit in channel 32 provided in the car side wall and on the permanent partition 34 between the storage bins. The lower part is provided with floor lock 36 and folding supporting brackets 38, one on either side, adapted to fold into a recess in the member and be retained by spring clip 40. The part T is formed with a lower part 42 to which is hinged the upper part 44 and each is provided along one edge with a channel receptacle 46 which fits over the outer 20 edge of part S and firmly holds the two in vertical position due to the staggered relation of the hinge connections. Top and bottom locks 36 and supporting brackets 38 are also provided which are similar in purpose to those previously described.

30 The top portion of part 44 is cut to conform to the permanent partition 34 and is provided with plates 48 adapted to receive the ends of curtain rods J.

The curtain rods, Fig. 10 adapted to support 35 curtains W, are formed of metal tubing 50 closed by caps 52 through which are extended rods 54 having head portions 56 adapted, when extended, to engage plates 48 of the partition. The inner end of the shaft carries a nut 58 forming an 40 abutment for spring 60, which spring tends to retract the rods and thus shorten the curtain rod in order that it may fit within the storage bins.

The storage bins F are hinged to the car structure and fill the space between the partitions 34 thus giving a smooth finished appearance to the coach. The bins are provided with cable and spring devices 62 which assist the operator in the handling of the bins, either in storage or removal of the contents. These bins are of ample 50 length and capacity to receive the partitions P, curtain rod J, mattress M, blankets O, pillows N and the member 16, as well as other necessities which are not shown.

55 The modification shown in Figs. 13 and 14 is very similar to the construction previously described and like numerals have been applied wherever necessary in order to avoid unnecessary repetition. The seats in this modification are 60 more nearly of the conventional type having pipe rails 64 instead of the sheet metal pressing of the other seat which, of course, requires a different type of supporting means 66. The support 66 is formed with an interrupted base portion 68 adapted to project forwardly to cover the slide rails and provide a smoother construction. The back portion 10 extends upwardly from the base and carries inclined lugs 72 adapted to interlock with the sides 5 of the seat backs in the 70 same manner as previously described.

In converting the car from a day coach to a sleeper it is only necessary to move the seat backs so the seats face each other, and remove the partitions and back supporting members 75 from the bin. The partitions are unfolded and

part S fitted into the channel groove, locked in place and the ledges 38 folded down; then part T is unfolded, placed and locked in position and the ledges 38 thereon folded down. The curtain rod is next engaged with the partition plates by 5 extending the rods 54 and the partition is held firmly in place. The lower part of the seat backs is next removed, the cushions lifted back upon the ledges and the support member placed on the seat cross member, after which the seat backs are 10 turned sidewise and interlocked with the support plate.

It is to be noted that by varying the width of the lower portions of the seat back the dressing space Y formed between the side portion of the 15 berth and the curtain may be increased or decreased as desired by the respective railroad or that by simply carrying extra seat back portions, both upper and lower parts of varying widths, it is possible for the railroad to vary the dressing space without any alteration in car design. It is also possible to carry an extra filler portion 20 to give a wider berth if this is desired or necessary.

These and other modifications may be made by one skilled in the art without departing from the scope of the following claims which define applicants' invention.

What is claimed is:

1. In a railway car, the interior of which resembles the conventional railway passenger car, seats within said car, the majority of said seats being capable of facing in either direction, removable partitions extending substantially from car floor to ceiling for dividing said car into compartments with at least two seats in each compartment, curtains extending between the partitions to close the compartments, said seats being so constructed as to cooperate with said partitions to form berths and provide dressing space 35 between the sides of the berths and said curtains.

2. In a railway passenger car, seats within said car, the majority of said seats being capable of facing in either direction, removable partitions for dividing said car into compartments containing at least two seats, said seats being so constructed as to be converted into berths by placing 45 at least a portion of the backs lengthwise between the seat cushions, and brackets on said partitions for supporting one edge of the adjacent seat 50 cushion.

3. In a railway passenger car, seats within said car, the majority of said seats being capable of facing in either direction, removable partitions for dividing said car into compartments containing at least two seats, said seats being so constructed as to be converted into berths by placing 55 at least a portion of the backs lengthwise between the seat cushions, and brackets on said partitions for supporting one edge of the adjacent seat cushion, the combined width of said backs being less than the width of said seats whereby space is provided for dressing.

4. In a railway car having seats adapted to face each other and convertible into berths, cushions 65 on said seats, seat backs each having removable portions adapted to bridge the space between the seat cushions, the combined width of said backs being less than the width of said seats whereby space is provided for dressing.

5. In a railway car having seats adapted to face each other and convertible into berths, partitions in said car inclosing at least two seats to form a compartment, curtains closing the compartment adjacent the seat ends, the central por- 75

tion of said berth being spaced sufficiently from said curtain to provide dressing space.

6. In a railway passenger car, seats within said car, the majority of said seats being capable of facing in either direction, removable partitions for dividing said car into compartments containing at least two seats, said seats being so constructed as to be converted into berths by placing at least a portion of the backs lengthwise between the seat cushions, means engageable with the seat structure and adapted to interlock with the side portions of the backs to support said backs substantially flush with the seat cushions.

7. In a railway passenger car, seats within said car, the majority of said seats being capable of facing in either direction, removable partitions for dividing said car into compartments containing at least two seats, said seats being so constructed as to be converted into berths by placing at least a portion of the backs lengthwise between the seat cushions, means engageable with the seat structure and adapted to support said backs substantially flush with the seat cushions, and brackets on said partitions for supporting one edge of the adjacent seat cushion.

8. In a railway passenger car, removable partitions supported on the car floor and adapted to divide said car into compartments, said partitions comprising two separable interfitting parts each of which is formed by hinged portions so proportioned as to permit folding of the partition after removal whereby it may occupy a minimum space.

9. In a railway passenger car, removable partitions supported on the car floor and adapted to divide said car into compartments, said partitions comprising at least two interengaging and separable parts, and a removable curtain rod adapted to be removably connected to the upper portion of one part of each partition whereby said partitions are tied together and stiffened lengthwise of the car.

10. In a railway passenger car, removable partitions adapted to divide said car into compartments, a curtain rod adapted to join said partitions, said rod comprising a tubular portion and retractable end portions engageable with the partitions, and springs for retracting said end portions, said springs and rods yieldingly tying said partitions together lengthwise of the car.

11. In a railway passenger car, removable partitions adapted to divide said car into compartments, a curtain rod extending between the adjacent partitions for stiffening the same lengthwise of the car, said rod comprising a tubular portion, headed means at either end extending into said tubular portion, resilient means to retract said headed means, said headed means being adapted to engage the adjacent partition

whereby the partitions are resiliently tied together.

12. In a railway passenger car, removable partitions adapted to divide said car into compartments, a curtain rod adapted to extend between the adjacent partitions, said rod being normally of less length than the distance between said partitions.

13. In a railway passenger car, removable partitions adapted to divide said car into compartments, said partitions each comprising two separable interfitting parts, each of which is formed by portions hinged together to form joints permitting folding of the parts, said joints in the respective parts being staggered, thereby forming a substantially rigid partition.

14. In a railway passenger car, walkover seats within the car, removable partitions supported on the car floor and adapted to divide the car into a plurality of compartments, said partitions comprising at least two separable interengaging sections each provided with recesses in the lower portions thereof, downfolding brackets within said recesses adapted when in use to support the edge portion of a seat cushion, and means in said recesses for retaining said brackets within their recesses when not in use.

15. In a railway passenger car, removable partitions supported on the car floor and adapted to divide said car into compartments, said partitions comprising two separable interfitting parts, each of which is formed by movable portions joined together by a hinge, said hinge joints being so staggered as to permit folding of the partition whereby it may occupy a minimum space for storage.

16. In a railway passenger car, removable partitions supported on the car floor when in use and adapted to divide said car into compartments, said partitions comprising two separable interfitting parts, each of which is formed by hingedly connected portions, said portions being of varying lengths whereby the partition may be folded into a minimum space when not in use.

17. In a railway passenger car, removable partitions supported on the car floor when in use and adapted to divide said car into compartments, said partitions comprising two separable interfitting parts, each of which is formed by relatively long and short hingedly connected portions, said short portions of the partition being of less length than one of the long portions whereby said partitions may be folded and nested when not in use to occupy a space substantially equal to three thicknesses of the partition.

55
